SYRINGE APPARATUS

Louis Gross, New York, N. Y.

Application January 20, 1933, Serial No. 652,653

7 Claims. (Cl. 128—214)

This invention relates to syringe apparatus, and it has among its objects syringe apparatus particularly adapted for blood transfusion and similar surgical operations, enabling positive and unidirectional transfusion of fluid with a simple, foolproof, valveless structure and requiring a minimum of attention in use.

The foregoing and other objects of the invention will be best understood from the following descriptions of exemplifications thereof, reference being had to the accompanying drawings, wherein

Fig. 1 is a horizontal sectional view of a syringe apparatus embodying the invention;

Fig. 2 is a vertical sectional view along line 2—2 of Fig. 1;

Fig. 3 is a vertical elevational view of the syringe shown in Fig. 1 provided with a special tip attachment;

Fig. 4 is a vertical sectional view through a portion of the syringe apparatus embodying a modified form of the invention;

Fig. 5 is a transverse vertical sectional view through the syringe apparatus along line 5—5 of Fig. 4; and

Fig. 6 is a developed view of the guide head of the syringe apparatus shown in Figs. 4 and 5.

In using blood transfusion apparatus for withdrawing blood from a donor and injecting it into a recipient, it is important that the apparatus be of utmost simplicity, have as few movable parts as possible, and that it positively assure unidirectional flow of the transfused fluid.

The present invention provides such syringe apparatus with only two movable parts, equipped with a simple and foolproof guide mechanism confining the relative movement of the two parts to a definite path and direction, insuring positive flow of the transfusion fluid from the donor to the recipient with a minimum of manipulations.

The exemplification of the invention shown in Figs. 1 to 3 comprises an elongated cylindrical pump barrel 11 having an interior cylindrical pump chamber 12 into which is slidably fitted a cylindrical piston 13, to permit longitudinal as well as rotational movement of the piston within the chamber, and provide a fluid tight joint between their contact surfaces. The pump barrel 11 as well as the piston 13 are made of a tight and refractory material, such as glass, the contact surfaces of the two members being ground to have a good fit. The bottom end of the chamber is closed by a flat bottom wall 14 against which a corresponding piston bottom wall 15 fits

to reduce to a minimum all dead air spaces between the barrel and piston walls when the latter is in its innermost position. The top end of the pump barrel 11 is provided with a reinforcing flange 16 and has an opening to permit insertion and withdrawal of the piston 13 from the interior of the barrel. The top end of the piston 13 is provided with a reduced neck portion 17 extending beyond the flange 16 of the barrel and terminating in a grip member 18 by means of which the piston 13 may be moved in and out, or rotated within the barrel. The piston with its neck portion and grip member are preferably made as a single unit, being preferably all of glass.

The pump barrel 11 is provided with a pair of nipples 20 and 21 extending outwardly from the opposite barrel walls at an intermediate portion of its length to provide a pair of ports 22 and 23 for communicating with the interior of the pump barrel.

Nipple 20 which serves as an inlet, has attached to it a tube 24, for instance, of rubber, as is used in connection with surgical apparatus, the other end of which is connected to a needle 25 which is inserted into the vein of the donor of the blood, a clamp 26 permitting closing of the tube 24. In a similar way, a rubber tube 27 is attached to the outlet nipple 21 on the other side of the pump barrel, the tube being connected to an injection needle 28 of the recipient of the blood, a clamp 29 serving to shut off the rubber tube 27.

The bottom wall 14 of the pump chamber 12 is also provided with a nipple 30 having an opening 31 for admitting fluid into the pump chamber, a rubber tube 32 closed by a clamp 33 being attached to nipple 30 to permit shutting off the bottom opening 31.

The outer surface of the cylindrical piston 13 has a cut-off longitudinal portion 35 which forms a longitudinal groove between the cylindrical barrel surface and the cut-off portion of the cylinder periphery, the groove 35 extending from the bottom of the piston till a point of its length where it overlaps the ports 22 and 23 when the piston is in inward position.

In Fig. 1 the groove 35 of the piston is shown lying opposite the inlet opening 22, establishing thereby a connection between the inlet opening and the bottom of the pump chamber in front of the piston chamber 15. In this position the outlet opening 23 is sealed up by the cylindrical surface of the piston. On rotating the piston 13, the nipple opening 22 becomes sealed up, and if

the piston is rotated 180°, the groove 35 comes to lie in front of the nipple opening 23 on the opposite side of the barrel, as indicated by the dotted line 35', establishing a connection between 5 the outlet opening 23 and the bottom of the pump chamber 12 in front of the piston bottom 15. Because of this arrangement, pulling out of the piston 13, while the piston groove 35 lies in front of port 22, will suck in blood through needle 25 inserted in the donor's vein, tube 24, inlet port 22, and then along piston groove 35 to the bottom portion of the pump chamber 12, filling the space in front of the piston bottom 15. By turning now 10 the piston 13 and bringing piston groove 35 opposite the port 23 and then pushing in the piston to its inward position, the blood pumped into the space in front of the piston bottom 15 in the outward stroke, is expelled through groove 35, port 23, tube 27, and needle 28, into the recipient 15 of the blood transfusion.

The blood is thus withdrawn from the donor by an outward stroke of the piston 13 and injected into the recipient by an inward stroke of the piston, without maintaining at any time any direct 25 communication between the donor and the recipient, and without using valves or any other movable parts besides the pump barrel and pump piston.

The syringe apparatus has, in addition, a simple and effective mechanism for controlling the movement of the piston within the pump barrel to permit ingress of fluid into the pumping chamber only through inlet port 22, and permit egress of fluid from the chamber only through outlet 30 port 23. In the construction shown, this is effected by confining the piston to longitudinal movement in outward direction only when the piston groove 35 lies opposite inlet port 22 of the pump while pumping blood from the donor into 35 pump chamber 12; and for confining the piston to longitudinal movement in inward direction only when the piston groove 35 lies opposite outlet port 23 while injecting blood from the pump chamber 12 into the recipient.

45 This mechanism comprises a rigid collar 40 having a lower half 41 and an upper half 42, with overlapping engaging edges clamped tightly around the flanged top portion of the pump barrel 13 by means of a cap 43 having a threaded 50 flange 44 screwed over a corresponding thread formed over the outer surfaces of the projecting rear portions of the collar halves.

The two outer sides of the upper collar half 42 are provided with a pair of ratchet bars 45 and 55 46, the ratchet teeth of bar 45 having a flat slope in outward, and a steep slope in inward direction, and the ratchet teeth of bar 46 having a flat slope in inward, and a steep slope in outward direction. A pair of outwardly extending guide 60 bars 47 and 48 extend from the outer sides of the lower collar half 41 directly below the lower edges of the ratchet teeth of the upper collar half 42. A resilient detent 49 having an inwardly bent catch 50 engaging the ratchet teeth of bars 45 or 65 46 is held by a collar 51 firmly attached to a portion of the piston neck 17, the detent catch 50 engaging the ratchet teeth and controlling by this engagement the outward and inward movement of the piston 13 within the pump barrel.

70 The collar 40 is clamped to the pump barrel 11, in a position in which the detent catch 50 is in engagement with the teeth of the ratchet strip 45 when the piston groove 35 is aligned with inlet port 22; and in engagement with the teeth of ratchet strip 46 when the piston groove 35 is

aligned with the outlet port 23. The piston 13 may be rotated by the turning of the knob 18 to swing the detent catch 50 from the ratchet bar 45 to ratchet bar 46 and vice versa, the swinging movement of the piston and the detent being limited by the guide bars 47 and 48 projecting outwardly from the sides of the lower collar half 41. These guide bars 47 and 48 thus serve as stops, limiting the swinging movement of the detent 49, and the corresponding rotary movement of the piston 13 from the position in which the piston groove 35 is in communication with inlet port 22 and the position in which the piston groove is in communication with the outlet port 23 of the pump barrel. 15

If the piston is pulled out for some length from the pump barrel and turned into any angular position in which the piston groove 35 does not overlie either inlet port 22 or outlet port 23, that is, into any position where the ratchet catch 50 20 does not engage the ratchet teeth along guide bars 47 or 48, longitudinal inward movement of the piston within the barrel will be prevented by the pressure of the fluid present in the chamber in front of the piston bottom 15; and longitudinal 25 outward movement of the piston will be prevented by the vacuum that would be created in the space in front of the piston bottom. Accordingly, longitudinal movement of the piston in the barrel will be confined only to the positions 30 in which the piston groove 35 lies in front of either inlet 22 or 23. In all other angular positions of the piston groove 35 in the barrel 11, the piston will be automatically held at the same height in the barrel. 35

Through the engagement of the detent end 50 with the guide bars 47 and 48, respectively, there is provided a firm longitudinal guide for the outward stroke of the piston when the piston groove 35 is in communication with the inlet port 22, 40 as well as for the inward stroke of the piston when the piston groove 35 is in communication with the outlet port 23, thus securing firm longitudinal guidance of the piston in the positions in which it is free to move longitudinally in the 45 barrel. Since the ratchet 45 has its teeth directed toward the top of the barrel, the detent catch 50 engaging these teeth will permit movement of the piston over this ratchet 45 only in outward direction, any attempt to move the piston inward 50 in this position being prevented by the steep sides of the ratchet teeth. On turning the piston 13 in its outward position till detent catch 50 engages the ratchet 46 on the other side of the syringe, the oppositely directed ratchet teeth will permit 55 only inward movement of the piston, an outward movement of the piston being prevented by the rearward direction of the teeth of ratchet 46. There is thus provided a very simple, but positive, guide for longitudinally moving the piston in outward direction while its piston groove 35 is in communication with inlet port 22, this movement being confined to the outward direction, end movement in inward direction being prevented by the ratchet arrangement. In a similar way, there is provided a positive guide for 60 moving the piston in inward direction while maintaining communication between the piston groove 35 with outlet port 23, and preventing other than inward movement in longitudinal direction by the ratchet engagement of the detent with the ratchet strip 46. 65

To enable determination of the quantity of fluid passing through the transfusion syringe, the upper wall of the barrel, a portion of which 70

is shown in Fig. 1, is provided with graduations indicating the volume of the chamber lying between the bottom wall 14 of the barrel 11 and the graduation mark.

5 The light, simple and handy syringe apparatus so far described is in itself sufficient to easily and safely administer blood transfusions. In operating the apparatus in connection with a blood transfusion, the syringe pump is first 10 primed with an auxiliary fluid, such as a saline solution, to expel the air from the interior space of the pump chamber and its connections. This is conveniently done by inserting the needle 25 of the tube 24 in a saline solution, while holding the tube 32 closed by clamp 33, and pumping saline solution into the space within tube 24 and the bottom opening 31 and the space within tube 27 and needle 28 leading to the recipient, and expelling all the air from the interior space. The 15 tubes 24 and 27 are then locked by the clamps 26 and 29, clamp 33 is opened, and tube 32 extending from the barrel bottom is placed in the saline solution container, and filled with saline solution, expelling any air bubbles that might have been left in the pump barrel. Thereupon, the 20 proper amount of saline solution required for the initial injection into the recipient is drawn into the pump chamber 12, the clamp 33 is closed, and the piston is rotated to have its recess 35 engaged 25 with the outlet port 23 of the barrel to permit injection of the saline solution into the recipient. With the injection of the saline solution completed, the piston is then turned to the left, with the 30 detent catch 50 gliding along the end groove 53 from ratchet 46 to the corresponding groove of ratchet 45 until the detent catch 50 comes into abutment against the guide bar 47, as shown in Fig. 2.

35 The piston groove 35 then connects the space in front of the bottom of the piston with the tubular line 24 going to the vein of the donor. The piston 13 is then pulled in outward direction, pumping blood through tube 24 into the pump chamber in front of the piston bottom 15 until the detent catch 50 reaches the upper ratchet groove 54 at which the outward stroke is stopped. Thereupon, the piston is rotated to the right, the ratchet catch 50 sliding from groove 54 of ratchet 45 into the corresponding groove of ratchet 46 until it comes into engagement with 40 guide bar 48, whereupon the piston is pushed inwardly, ejecting the blood from the pump chamber through port 23 and injecting it through needle 28 into the recipient. Any quantity of blood 45 can be thus transfused from the donor to the recipient by repeating this operation.

50 The maximum length of the pumping stroke is limited by the length of the ratchet bars 45 and 46, this length being chosen to suit best the usual operations. When a quantity of blood, less than corresponding to the full stroke is to be 55 transfused, for instance, only 2 cubic centimeters, indicated by the graduation mark "2" on the top of the barrel, the piston 13 is first brought to its inward position, with the groove 35 opposite the inlet port 22, and detent catch 50 in the lowest groove of ratchet 45, and then pulled out along guide 47 till the piston bottom 15 registers with the mark "2" on the barrel. Thereupon, the piston, being held by the sealed fluid in the pump chamber in the same longitudinal position, is rotated till the detent catch 50 reaches guide 48 on the opposite side of the barrel, and pushed into the barrel, expelling the 2 cubic centimeters 60 blood and injecting them into the recipient.

65 It is also easy to adjust the piston to operate with a maximum stroke of any value, smaller than the full length of the ratchets 45 and 46, for instance, 5 cubic centimeters, by loosening with wing screw 49' clamping the slotted end of the detent 49 to the projecting arm of piston collar 51, and shifting the detent 49 upwardly to the position at which it overlaps only a ratchet portion corresponding to a stroke sufficient to withdraw the piston to the "5" cubic centimeter mark, 10 and clamping the detent by the wing screw 49 in the new position. The piston will then be limited in outward movement to a point at which a maximum pump volume of 5 cubic centimeters 15 will be created in the pump chamber 12.

20 The constricted path of piston movement eliminates the possibility of mistakes through oversight or excitement. The operation can only be carried out in the definite constricted way, namely by moving the piston only in outward direction 25 while its groove 35 is engaged with the blood inlet 22, and its inward movement is absolutely prevented; rotation of the piston from the outward guide bar to the inward guide bar, while longitudinal movement of the piston is prevented; and inward movement of the piston to inject the blood 30 into the recipient, with back movement positively prevented. With a light and simple instrument, it is thus possible to perform operations for which heretofore complicated, expensive and cumbersome apparatus had to be used.

35 Where circumstances make it desirable, the syringe apparatus may be mounted during use on a simple support. This support is shown in Figs. 1 and 3 and comprises a base plate 61 of suitable material, such as metal, having rigidly secured thereto a pair of upstanding posts 62 and 63, likewise of strong material, such as metal. The upper portion of post 62 is hollow and has a longitudinal slot 64 for clamping and firmly holding bolt 65 rigidly secured to the underside of the lower collar half 41. By pushing down the syringe, the bolt 65 enters into the slotted opening 63 of the post 62 and is resiliently gripped thereby so that a good holding connection is obtained between the base 61 and the collar.

40 The top of the other post 63 carries a resilient sheet metal clamp, with the upwardly projecting sides 66 conforming to the lower half of the piston barrel 11, embracing the sides of the pump 45 barrel and thereby assist post 62 in holding the syringe barrel and the associated elements firmly in position. Suitable cutouts 67 are provided in the clamping sides 66 for accommodating the nipples 20 and 21 of the barrel. The syringe support 50 thus forms a very stable unit for holding the syringe during the transfusion operation on a table or the like, the distance between the supporting posts 62 and 63 permitting convenient gripping of the entire unit in the hand of the 55 physician administering the transfusion.

60 The syringe apparatus is also equipped to permit direct mounting of an injection needle on the pump barrel of the syringe, and to operate the syringe with the injection needle as a single 65 unit, like an ordinary injection syringe.

65 As shown in Fig. 3, the nipple 30 on the bottom 70 14 of the syringe barrel may have mounted thereon an adapter 71 having a tubular inlet chamber 72 provided with a head 73 tightly fitting the outer surface of the nipple 30 and held tight thereon by a spring clamp 74 anchored at the base of nipple 30. The inlet chamber 72 of the adapter 71 has on one side an inlet pipe 75 for admitting thereto an auxiliary fluid, such as 75

saline solution, through a rubber tube 32 having a clamp 33, like in the arrangement shown in Fig. 1. The adapter 71 has further an outlet chamber 76 with an inlet nipple 77 connected by a rubber tube 78 to the outlet nipple 21 of the pump barrel 11 through which the blood that is to be injected is fed from the pump chamber to the outlet chamber 76 when the piston 13 is moved inwardly along the guide bar 48 of the 10 syringe collar 40. The inlet chamber 76 of the adapter has an outlet nipple 79, similar to outlet nipple 30 of the pump barrel, to which is attached a closely fitting injection needle 80 anchored by a spring attachment 81 on the nipple 15 79.

With the adapter so mounted and arranged on the syringe, the unit as a whole may be used like an ordinary needle syringe, and permit continuous transfusion of blood pumped from a donor 20 through inlet 22 of the syringe barrel and injected into the passage to the injection needle 80 held directly on the end of the syringe. When so operated, the syringe support 60 may be used with the syringe as a unit, or may be taken off 25 25 from the syringe apparatus.

In Figs. 4, 5 and 6 there is shown a modified form of the syringe apparatus of my invention in which the syringe barrel is provided with more than two lateral ports, each sealed by the 30 cylindrical surface of the piston, and arranged for selective alignment with the longitudinal groove of the piston, and longitudinal movement in constricted directions for confining the flow of the transfused fluid through the individual 35 ports in a predetermined unidirectional way.

As shown in Fig. 4, the pump barrel 101 and the piston 102 are constructed like those of the arrangement in Figs. 1 to 3, the bottom 103 of the barrel being flat and without an outlet opening. To the top of the pump barrel 101 is secured a collar guide attachment 104 of modified construction. It comprises a lower collar half 105 and an upper collar half 106 with overlapping 40 engaging edges clamped tightly around the flanged top portion of the pump barrel 101 by means of a threaded ring 107, as in the prior embodiment. The barrel has three nipple ports 111, 112 and 113 spaced angularly along the periphery of the barrel at an intermediate portion 45 of the length thereof, and the collar is provided with three ratchet bars 114, 115 and 116 aligned with the three nipple ports.

A resilient detent 118 with an inwardly turned catch 119 is carried by an outwardly projecting 50 arm of a collar 120 clamped to the neck portion of the piston, like in the prior modification, to be turned from one ratchet bar to another and permit longitudinal movement of the piston in inward or outward direction, depending on the 55 slope of the teeth of the individual ratchets. The piston has a cut-off surface along a portion of the length thereof, to form a groove 121 with the cylindrical wall of the pump barrel 101. The attachment of the detent 118 to the piston is set 60 to have the detent catch engage the ratchet bar which is aligned with the barrel port lying opposite the piston groove 121.

One mode of arranging the three sets of ratchet bars on the guide collar is indicated by way 65 of example in the developed view of the guide collar shown in Fig. 6. In the two outer ratchet bars 114 and 115, the teeth are sloped in the direction towards the top of the barrel, permitting outward movement of the piston in the pump 70 barrel in each of these positions. In the inter-

mediate ratchet bar 115, the slope of the ratchet teeth is in the opposite direction, permitting movement of the piston only in inward direction into the piston. With this arrangement it is possible to set the piston into engagement with ratchet 114 for pumping a fluid, for instance, a saline solution, through port 111 as saline inlet port, then turn the piston and set it into engagement with ratchet teeth 115 and inject the saline solution from the barrel through the central outlet port 112 into a recipient, and then turn the piston and set it into engagement with ratchet 116, to pump blood through blood inlet port 113, and then continue the blood transfusion operation between blood inlet port 113 and blood 15 outlet port 112.

Longitudinal guides, in the form of barrier bars 121 and 123, are provided at the lower edges of the ratchets 114 and 116 to provide a longitudinal guide for the detent 118 in its outward movements. The intermediate ratchet bar 115 is provided with a pair of special notched guide bars 127, in the form of longitudinal members, lying on both sides of the ratchet bar 115, and confining the detent catch member 119 in its longitudinal movement to the space above the ratchet teeth to guide the inward movement of the piston in the position at which the piston groove 121 is in engagement with outlet port 112 to eject the fluid from the pump chamber. 30 These guide barriers 127 are not continuous, but have notches 128 opposite the gap portions of the ratchet teeth so that when in this position, that means at the end of each ratchet tooth, the detent catch 119 can be turned laterally, 35 either to the right, or left, and swung over either to the ratchet member 114 on one side, or the ratchet member 116 on the other side. This lateral swinging movement is, however, subject to an additional control by two locking bars 141 40 longitudinally slideable in channels formed between the outer sides of the notched bars 127 and similarly notched outer supporting bars 112 projecting above the collar surface.

The locking bars 141 have a limited longitudinal movement, by the sliding engagement of the front end 134 of each bar within a guiding groove 135 in the outward flange of the collar, and the sliding engagement of the rear end 136 of each locking bar in a groove 138 formed in the rear flange 139 of the collar, the two halves of which are held clamped to the pump barrel by means of a threaded ring 140. A knurled knob projects from each locking bar above the level of the collar flange 139 to permit pushing of the 50 locking bar 141 forward and back in its guide channel.

Each locking bar 141 has a plurality of projecting teeth 142 which lie between the upstanding guide members 127. As shown in Fig. 6, 60 these teeth 142 lie in a position at which they uncover the notches 128 in the guide barriers 127 so that in this position the notches 128 are open. To keep the lock bar in this position, it is provided with a metal locking pin 147 located in a channel 145 within the locking bar and pressed down by a spring to engage a groove in the underlying collar surface and be kept by the spring in this position. By pushing the knob 101 of the lock bar in outward direction, the spring holding 70 the locking pin 136 yields and the locking bar moves forward till its teeth 142 cover up the notches 128 in the guide bar and block lateral movement of the detent catch, preventing lateral rotation of the piston. The locking pin 136 en- 75

gages then another groove in the underlying collar surface so that the locking bar is now locked in the new position in which lateral movement of the detent catch 119 from the ratchet guide is 5 blocked.

The locking bars 131 on both sides of ratchet 115 may thus be independently moved from the position in which they lock the lateral movement of the detent and piston, or permit lateral movement 10 of the detent and the piston.

With the foregoing arrangement, barrel outlet 112 may be arranged to confine its cooperation either to inlet 111 or to inlet 113. For instance, if inlet 111 is to pump an auxiliary fluid, such as 15 a saline solution, into the recipient, the lock bar 141 on the left side of ratchet 115 is opened, and on the right side is closed, limiting swinging movement of the detent between ratchet bar 114 and ratchet bar 115 and permitting only pumping 20 of fluid into the pump chamber by pulling out the piston along ratchet 114 and ejecting the fluid into the recipient by turning at the end of the stroke the piston till the detent comes into engagement with ratchet 115, and thereupon pushing 25 the piston in and injecting the fluid into the recipient. If the inlet 116 is to be used with outlet 115 of the pump barrel, lock bar 141 on the side of the ratchet 115 facing ratchet 116 is unlocked, and lock bar 141 on the other side of 30 ratchet 115 is locked, and the piston is similarly manipulated to be moved outwardly and pump along ratchet 116, then turned in outward position for engagement with ratchet 115, and then pushed inward to eject the blood through outlet 35 port 112. This insures perfect unidirectional movement and guidance of the piston in each of its strokes.

If care is used, it is also possible to operate in sequence all three inlets, leaving both locking 40 bars of the intermediate ratchet 115 in unlocked position, since the notched guide bars 127 on both sides of the intermediate ratchet 115 gives sufficient guidance for the detent catch to permit positive handling of the instrument when used 45 with unlocked guide bars 127.

The invention is not limited to the details of construction and materials described above, nor to the use for blood transfusion, but is generally applicable in various other surgical apparatus in 50 which similar operations have to be carried out. Accordingly, it is desired that the appended claims be given a broad construction commensurate with the scope of the invention.

I claim:

1. A syringe apparatus comprising a cylindrical pump barrel having a pump chamber closed at one end and open at the opposite end, a cylindrical pump piston fitting said pump barrel and movable therein between an outward position 55 wherein its bottom encloses the open end of the pump chamber and an inward position wherein it fills said pump chamber and overlaps an outward portion of said barrel adjoining said chamber and occupied by said piston in the outward position, a pair of peripherally displaced ports in said outward barrel portion covered by the piston walls over its entire stroke range, a longitudinal recess on the cylindrical piston surface extending from its bottom to a height sufficient to overlap the peripheral region of said ports when the piston 60 bottom is in contact with the barrel bottom, one of said pump members having secured thereto a pair of ratchet members longitudinally aligned with said ports, respectively, the other of said pump members having secured thereto detent 65 means for engaging either one or the other of said ratchet members, the slope of the teeth of one of said ratchet members limiting the movement of the detent means thereon to restrict the movement of the piston in the barrel to outward direction and the slope of the teeth of the other of said ratchet members limiting the movement of the detent means thereon to restrict the movement of the piston in the barrel to inward direction, for confining the inward stroke of the piston 70 to the position of alignment of the piston recess with one of said ports and for confining the outward stroke of the piston to the position of alignment of the piston recess with the other of said ports.
4. A syringe apparatus comprising a cylindrical pump barrel having a part forming a pump chamber with a transverse bottom wall constituting the inward end of said chamber, a cylindrical pump piston fitting said pump barrel and 75

inward stroke of the piston to the position of alignment of the piston recess with one of said ports and for confining the outward stroke of the piston to the position of alignment of the piston recess with the other of said ports.

2. A syringe apparatus comprising a cylindrical pump barrel having a part forming a pump chamber with a transverse bottom wall constituting the inward end of said chamber, a cylindrical pump piston fitting said pump barrel and movable 10 therein between an outward position wherein its bottom forms the outward end of said chamber and an inward position wherein it fills said pump chamber and overlaps an exterior portion of said barrel adjacent said pump chamber occupied by 15 the piston in the outward position, a pair of peripherally displaced ports in said outward barrel portion covered by the piston walls over its entire stroke range, a longitudinal recess on the cylindrical piston surface extending from its bottom to a height sufficient to overlap the peripheral region of said ports when the piston bottom is in contact with the barrel bottom, one of said pump members having secured thereto a pair of 20 guide members, each coordinated with one of said ports, and the other of said pump members having an additional guide member cooperating with said pair of guide members for confining the inward stroke of the piston to the position of alignment of the piston recess with one of said 25 ports and for confining the outward stroke of the piston to the position of alignment of the piston recess with the other of said ports.

3. In a syringe apparatus, a pair of pump members comprising a cylindrical pump barrel having a pump chamber closed at one end and open at the opposite end and a cylindrical pump piston fitting said barrel, said piston being movable 35 between an outward position in said barrel wherein it bounds the open end of said pump chamber, and an inward position wherein it fills said pump chamber and overlaps an exterior portion of said barrel adjacent said pump chamber occupied by the piston in the outward position, a pair of peripherally displaced ports in said outward barrel portion covered by the piston walls over its entire stroke range, a longitudinal recess on the cylindrical piston surface extending from 40 its bottom to a height sufficient to overlap the peripheral region of said ports when the piston bottom is in contact with the barrel bottom, one of said pump members having secured thereto a pair of ratchet members longitudinally aligned with the said ports, respectively, the other of said 45 pump members having secured thereto detent means for engaging either one or the other of said ratchet members, the slope of the teeth of one of said ratchet members limiting the movement of the piston in the barrel to outward direction and the slope of the teeth of the other of said ratchet members limiting the movement of the detent means thereon to restrict the movement of the piston in the barrel to inward direction, for confining the inward stroke of the piston 50 to the position of alignment of the piston recess with one of said ports and for confining the outward stroke of the piston to the position of alignment of the piston recess with the other of said ports.

4. In a syringe apparatus, a pair of pump members comprising a cylindrical pump barrel having a part forming a pump chamber with a transverse bottom wall constituting the inward end of said chamber, a cylindrical pump piston fitting said pump barrel and 55

- movable therein between an outward position wherein its bottom forms the outward end of said chamber and an inward position wherein it fills said pump chamber and overlaps an outward portion of said barrel adjoining said chamber and occupied by said piston in the outward position, a pair of peripherally displaced ports in said outward barrel portion covered by the piston walls over its entire stroke range, a longitudinal recess on the cylindrical piston surface extending from its bottom to a height sufficient to overlap the peripheral region of said ports when the piston bottom is in contact with the barrel bottom, and ratchet means secured to said barrel and detent means secured to said piston and engaging said ratchet means to constrict the longitudinal movement of said piston in said barrel to inward direction only when said recess is aligned with one of said ports and to outward direction only when said recess is aligned with the other of said ports.
5. A syringe apparatus comprising a cylindrical pump barrel having a pump chamber closed at one end and open at the opposite end, a cylindrical pump piston fitting said pump barrel and movable therein between an outward position wherein its bottom encloses the open end of the pump chamber and an inward position wherein it fills said pump chamber and overlaps an outward portion of said barrel adjoining said chamber and occupied by said piston in the outward position, an inlet port and an outlet port peripherally displaced in said outward barrel portion covered by the piston walls over its entire stroke range, a longitudinal recess on the cylindrical piston surface extending from its bottom to a height sufficient to overlap the peripheral region of said ports when the piston bottom is in contact with the barrel bottom, an inlet ratchet and an outlet ratchet longitudinally secured to different peripheral portions of said barrel, and detent means secured to said piston to rotate with said piston from a position of engagement with one of said ratchets to a position of engagement with the other of said ratchets, the positions of said ratchets being correlated to the positions of said ports to hold the piston recess aligned with the inlet port during engagement between the detent means and the inlet ratchet and aligned with said outlet port during engagement between the detent means and the outlet ratchet, said inlet ratchet having outwardly sloped teeth to restrict movement of the detent thereon only to a direction at which the piston is pulled out of the barrel and said outlet ratchet having inwardly sloped teeth to restrict movement of the detent thereon only to a direction at which the piston is pushed into the barrel.
6. A syringe apparatus comprising a cylindrical pump barrel having a part forming a pump chamber with a transverse bottom wall constituting the inward end of said chamber, a cylindrical pump piston fitting said pump barrel and movable therein between an outward position wherein its bottom forms the outward end of said chamber and an inward position wherein it fills said pump chamber and overlaps an outward portion of said barrel adjoining said chamber and occupied by said piston in the outward position, an inlet port and an outlet port peripherally displaced in said outward barrel portion covered by the piston walls over its entire stroke range, a longitudinal recess on the cylindrical piston surface extending from its bottom to a height sufficient to overlap the peripheral region of said ports when the piston bottom is in contact with the barrel bottom, ratchet means secured to said barrel and detent means secured to said piston and engaging said ratchet means, and additional means for confining the movement of said detent means to the longitudinal direction while in engagement with either of said ratchets.
7. A syringe apparatus comprising a cylindrical pump barrel having a pump chamber closed at one end and open at the opposite end, a cylindrical pump piston fitting said pump barrel and movable therein between an outward position wherein its bottom closes the open end of the pump chamber and an inward position wherein it fills said pump chamber and overlaps an outward portion of said barrel adjoining said chamber and occupied by said piston in the outward position, an inlet port and an outlet port peripherally displaced in said outward barrel portion covered by the piston walls over its entire stroke range, a longitudinal recess on the cylindrical piston surface extending from its bottom to a height sufficient to overlap the peripheral region of said ports when the piston bottom is in contact with the barrel bottom, guide means interconnecting said piston and said barrel for confining the inward stroke of the piston to the position of alignment of the piston recess with said outlet ports and for confining the outward stroke of the piston to the position of alignment of the piston recess with said inlet port, means for attaching the base of a forwardly projecting injection needle to the closed end of said barrel in alignment therewith, said needle having a fluid inlet at its base, and a tubular connection between the outlet port of said barrel and the inlet of said needle base for producing a direct flow of fluid from said pump chamber into said injection needle on pushing the piston into the pump barrel.

LOUIS GROSS.
